United States Patent Office.

JOHN A. THOMPSON, OF AUBURN, NEW YORK.

Letters Patent No. 82,365, dated September 22, 1868.

IMPROVED REFRIGERATOR AND SIDEBOARD.

The Schedule referred to in these Letters Patent and making part of the same.

Be it known that I, JOHN A. THOMPSON, of the city of Auburn, in the county of Cayuga, and State of New York, have invented a new and useful Improvement on Refrigerators and Sideboards combined; and I do declare that the following is a full, clear, and exact description of the construction and operation of the same, reference being had to the annexed drawings, making a part of this specification, in which—

Figure 1 is a perspective view of the sideboard.

Figure 2, a perspective view of the refrigerator.

Figure 3 is a sectional view of the refrigerator.

Figure 4, a section of angular post.

Figure 5 is an interior view.

A, in fig. 1, is the ice-box; B B, air-tight compartments; C C, provision-chambers; D D, ventilators; E, faucet; F, section of inside lining, cut so as to admit the stucco or concrete filling; G external covering; G', inner wall, of same material as external; K, ribs or anchors to fix filling to walls; H, concrete-filled space; I, air-space; J, inmost lining.

Fig. 4. L, a section of angular post, cap, or sill.

I construct my refrigerator and sideboard by first making a frame of suitable wood, sawing my posts, sills, and caps, in angular form, as represented in section, fig. 4, at L. These are framed together, and tied by girths of hoop-iron, or strips of thin wood, extending from sill to cap, and from post to post, attached by screws, nails, or dove-tailed, flush with outer face of frame. The edges of these should be bevelled, same as ribs K, to hold the concrete. I now cover this frame with a board, manufactured similar to trunk-boards, or first providing a web of strong cloth, woven open, from manilla, or other strong and cheap suitable material, one side being covered with any suitable pulp, or by strong paper, adhered to its surface by means of a water-proof size, and pressed, so as to furnish a smooth face or finish, or at the same time, by means of dies, medallion or embossed figures, mouldings, and ornamental designs, may be placed upon its panels. This material is cut to size, and glued, pasted, and nailed firm to the outer edges of the posts, caps, sills, and door-frame. A lighter but similar material is nailed on the inner angle of the frame. This is also adhered to the posts, sills, and caps by adhesive water-proof paste or glue, and nailed.

The space between the outer and inner wall I fill with a concrete, composed of plaster of Paris or gypsum, with its water of crystallization driven off, and granulated charcoal, from hard wood or anthracite coal, broken, so as to pass an eighth-inch-mesh sieve. These are mixed in about equal quantities when dry, and water is then added, so as to run readily, and fill the space by injection through the cuts marked F. The ribs K are nailed to the inner face of these walls, so as to bind the concrete and walls firm together, after filling. An inner wall is nailed to strips one-quarter inch thick, and the whole is nailed and adhered to the inner wall and frame by nails, glue, and paste, so as to form an air-chamber. This may be of trunk-board or web of cloth, finished water-proof on the inside by paste, glue, seedlac, or shellac, and painted with graphite, or finely-ground anthracite coal, or a metal lining instead, as preferred. The air-space at bottom should be covered by board, or corked, so a stratum of the concrete may be placed on the bottom; and a final covering of thin boards, attached by screws or nails to the sills, closes all.

The door and ice-chamber openings are enclosed by nailing lining to their posts, with glue or paste between.

The doors are made of thin narrow strips, framed together at their corners, and a surrounding of leather, or felt, or other suitable material, is glued on its face, and passed loosely around its edge, and glued upon its opposite face. Over this, an ornamented covering of the same material as the outer wall is nailed, and glued to the sides, and the space filled with concrete. At this stage, the whole is perfectly dried, its surface smoothed, painted, or japanned, so as to render all water-proof. The outside is now finished by suitable ornamental mouldings from wood, oiled, varnished, or painted, so as to harmonize with the finish of the room.

The base-moulding drops, so as to exclude a view of the board bottom.

The mouldings should be attached by ornamental screws, cast, or are made fast by a corner-box of sheet or cast metal, encasing the corners of lower mouldings, or may be attached to the board bottom and base.

I construct two air-tight compartments, one on each side of the ice-box. These compartments, B B, are enclosed, so as to be freed from all odor from provisions in chambers C C, or from moisture. The cold air circulates around them, and reduces the temperature, by conduction of the heat.

These chambers are provided with doors, closing on packing, air-tight, by means of an air-cock, entering the box.

The air can be displaced by an air-pump, and choice fruits or perishable articles preserved for use at pleasure.

Ice-box A extends to the bottom of the refrigerator, and is provided with a strong wire or wood rack on sides and bottom, as seen at O, into which the ice may be dropped. Beneath the bottom of this rack, apertures m m pass through the sides, and enter the enclosed conductors n n, and are let into the provision-chamber C C near the top. These conductors are soldered at their bottom and sides tight to walls of the ice-box. The air passes into the ice-box, and down to apertures m m, up through conductors n n, out at top of chambers C C, down, and out at ventilators at bottom of doors D D.

Fig. 1 shows a sideboard, which may be used in combination or separate from the refrigerator, being constructed of the same materials, and in the same manner as the refrigerator, omitting the ice-box and metal lining, thus furnishing a dry and suitable cabinet for the keeping of linens and other choice goods, free from mould, or the ravages of vermin.

Having thus described my invention, what I claim, is—

The construction of refrigerators and household-preservatories of angle-wood, skeleton-frames, with their entire walls of trunk-board, or its equivalent, filled with a concrete of plaster of Paris and granulated carbon, or other suitable material securing the same effects, all as specified and set forth.

In testimony that I claim the foregoing, I hereunto affix my signature, in presence of—

JOHN A. THOMPSON.
